(57) **CLAIM**

The ornamental design for a set of shoe sleeves, as shown and described.

DESCRIPTION

FIG. 1 is a top plan illustrative view of a set of shoe sleeves of the present design in an unconnected configuration;
FIG. 2 is a right side illustrative view thereof;
FIG. 3 is a perspective view thereof shown in a connected configuration;
FIG. 4 is a top plan view shown in an unconnected configuration;
FIG. 5 is a top plan view shown in a connected configuration;
FIG. 6 is a bottom plan view in a connected configuration;
FIG. 7 is a front elevational view thereof;
FIG. 8 is a rear side elevational view thereof;
FIG. 9 is a left elevational view thereof;
FIG. 10 is a right elevational view thereof;
FIG. 11 is a top plan illustrative view thereof;
FIG. 12 is a top plan illustrative view of FIG. 10;
FIG. 13 is a bottom plan illustrative view of FIG. 10;
FIG. 14 is another top plan illustrative view thereof;
FIG. 15 is a right side illustrative view of FIG. 14; and,
FIG. 16 is a left side illustrative view of FIG. 14.
The broken lines, positioned at the center and edges of the shoe sleeve, represent the attaching structure for the set of shoe sleeves and straps. The broken lines of a person represent a user of the set of shoe sleeves. The broken line representations are for illustrative purposes only and form no part of the claimed design.
